GUNNER'S WARNING PANEL AND LAMP
SYSTEMCharles L. Paulus and Raymond K. Stout,
Dayton, Ohio

Application March 20, 1943, Serial No. 479,870

6 Claims. (Cl. 177—337)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to improvements in signalling devices and more particularly to warning systems for gunners in aircraft and the like in which a plurality of gunners' stations are located, each covering predetermined areas around the craft.

An object of the invention is the provision of signal means which is operative from any of the gunners' stations to warn all of the stations of the presence or movement of an enemy craft or target in any one or more of the areas covered by the stations.

Another object is the provision of visual signal means arranged in or adjacent a plurality of associated gunners' stations, and signal operating means therefor in each station for actuating the signal means in all of the stations to inform the gunners therein of the presence of an enemy target in any particular area covered by any one or more of the stations.

A further object is to provide a visual signalling system depicting the areas covered by the gunners' stations and a visual signal associated with each of the areas depicted, operable from any of the gunners' stations.

A still further object is the provision of signal means and interconnected signal operating means in each of the gunners' station arranged in similar relation to the actual location of the gunners' stations and actual areas covered thereby.

Another object is the provision of signalling means located in all of the gunners' stations having depicted thereon the representation of the areas covered by the stations, and including interconnected visible signal and signal operating means arranged in each of the depicted areas for actuating the visible signal means in the same depicted areas on the signalling means in all of the stations.

Another object is the provision of multiple signal means located in each of the depicted areas on the signalling means, and interconnected similarly located multiple signal operating means for energizing any one of the multiple signal means in any of the depicted areas to warn the gunner's station covering said area not only that an enemy target is in the area, but that an enemy craft is above, on, or below the horizon level in said area.

A further object is the provision of test means on each of the panel members arranged to cause

simultaneous actuation of all of the signal means on each of said panel members.

Other objects and advantages of the invention will appear in the following specification, reference being had to the accompanying drawings in which like reference characters refer to like parts.

Fig. 1 is a somewhat diagrammatic side elevation of the rear portion of an airplane embodying my invention, and illustrating the representation of an enemy aircraft passing around the rear end thereof from the area covered by the starboard gunner into the area covered by the port gunner.

Fig. 2 is a plan view of one of the signal panels illustrating the arrangement of the signal lamps and associated signal actuating buttons.

Fig. 3 is a perspective view of one of the combined signal lamp and signal operating units.

Fig. 4 is a plan view of a modified form of signal lamp and signal operating unit.

Fig. 5 is a fragmentary view disclosing a wiring diagram for a four-station gunner warning system arrangement, in which only three of the gunners' stations are shown.

25 In modern war planes, particularly the larger bomber and patrol units, the gunners' stations are located at various places around the craft to cover various angles of approach. The locations of these stations are in the nose, tail, and on the sides, top and bottom of an aircraft. Some of these areas overlap, so that it is possible to concentrate the gunfire on a target from several different gunners' stations.

When an enemy plane is on one side of the 35 craft, in the area covered by certain of the gunners' stations, and passes to the other side, into the range or area covered by other gunners' stations, and if the gunners in the last mentioned stations immediately observe the enemy in their 40 area, they can quickly concentrate their gunfire on the target. These targets, however, are hard to immediately pick up, especially at night, and considerable valuable time is often lost before the target can be located and gunfire concentrated thereon. Interconnected telephones are often used in aircraft to inform the gunners' stations of the presence of an enemy in their area, or of the approach of the target toward their area, but these phones are often in use for other 45 purposes during contact with the enemy and considerable confusion and delay is therefore likely to occur with this system before the message is received and properly interpreted by the gunner.

Referring to Fig. 1 of the drawings, the rear 50 portion of a plane such as a large bomber is in-

dicated at A, and is provided with a plurality of gunners' stations for protecting the various portions of the craft, the guns in these stations covering adjacent areas or segments around the plane, including a rear gunner's station 1, and the left or port gunner's station 2.

An enemy plane or target 3 is illustrated as moving from a position 4 in the area or segment covered by the starboard gunner to a position in the area covered by the port gunner 2 and the tail gunner 1. The dot-and-dash line 5 indicates the probable direction of the enemy plane through the area just referred to, to a point 6, covered by both the port gunner 2 and the tail gunner 1. By the utilization of my improved visual signalling system, the port gunner is notified in advance that the enemy is moving into his sector, and he is in a position to concentrate his gunfire on the enemy as it moves into range.

In each of the gunners' stations in the craft, such as the nose, sides, top and bottom stations (not shown) and the two stations illustrated in Fig. 1, is located at least one of my improved interconnected visual signal devices, indicated generally at 7.

Each signal device includes a panel member 7a as illustrated in Fig. 2, having depicted thereon the graphic representation 8, preferably a plan view of the craft having the aforesaid gunners' stations and the areas covered thereby. This representation is located centrally on the panel member 7a with an area 9 surrounding the same having located therein a plurality of signal lamps, 10, 11, 12, 13, 14, 15, 16 and 17. These lamps are placed in the area 9, outside the outline of the aircraft 8 and in substantially the same relation that the areas or segments covered by the various gunners' stations occupy with relation to the plane.

For example, the center of the area covered by the rear or tail gunner's station 1 is directly behind the aircraft and is depicted on all of the panel members by the signal lamps 10, located in the rear of the depicted aircrafts. The port and starboard gunners' stations, respectively, cover areas to the left and right of the plane, and these areas are depicted on all of the panel members by the signal lamps 11 and 17, arranged in the same relation with respect to the aircraft outlines, in approximately the center of the segments illustrated on the panels.

Signal lamps 12 and 16 are positioned on the panel members to indicate the approximate adjacent ends of the segments covered by the side gunners' stations.

Lamps or other illuminating means 13, 15 and 14 are placed on the panels in front of the depicted craft and to the right and left in front of the wings to indicate the segments covered by the gunners in front or nose of the plane and at the right and left, in front of the wings. Signal lamp operating means 10', 11', 12', 13', 14', 15', 16' and 17' are arranged on each panel member 7a, close to the signal lamps 10 to 17, and in the same locations as the lamps.

These operating means consist of push button contacts which are mounted in the form of units, as seen in Fig. 3, each unit consisting of an elongated base member 18 apertured at its ends to receive one of the lamp sockets 19 at one end and one of the push button sockets 20 at the other end. The lamps and push buttons may be of conventional construction, including terminals 21, 22 and 23, 24, respectively, adapted

to be connected to conductors, as seen in the wiring diagram disclosed in part in Fig. 5.

As before indicated, at least one of the signalling devices 7 is placed in each of the gunners' stations on the aircraft, with lamps in the same location on all of the panels. The lamps for each location are connected in parallel in a circuit arranged to be energized by any of the push button switches disposed next to the respective lamps.

Referring again to Fig. 2, if a gunner in any of the gunners' stations depresses the push button 10' on a panel member 7a in his station, the signal lamp 10 on his panel will be lighted, as well as the signal lamps 10 on all of the other panels. And likewise, the switches or push buttons 11' or 12' on any of the panels will light the lamps 11 or 12 respectively on all of the panels.

In order to assure the gunners in the stations that the circuits and lamps on their panels are in proper working order, a test switch in the form of a push button 25 is provided on each panel member 7a, and the depression of this button energizes a circuit including all of the lamps 10 to 17 on all the panels.

In connecting the signal devices in the various gunners' stations, any suitable wiring circuit may be employed. An example is disclosed in Fig. 5, in which only three gunners' stations are illustrated, indicated generally as 26, 27 and 28. The use of a greater number of stations, as disclosed on the panel member 7a in Fig. 2, is largely a matter of choice, and it is therefore thought unnecessary to include more than three stations in the wiring diagram. It should also be noted that the diagram discloses only four signal lamps 10, 12, 14 and 16, and associated circuit closing devices or push buttons 10', 12', 14' and 16', but the addition of a larger number, such as 8, as disclosed on the panel member in Fig. 2, is also a matter of choice, depending upon the number of gunners' stations on the craft. In the wiring diagram, a test switch is provided as indicated at 25.

One terminal of each of the lamps 10, 12, 14 and 16, as disclosed in the wiring diagram, is grounded, as indicated at 30 to the metal framework or other suitable part of the craft through the terminal 21, while the other lamp terminals are connected by conductors 39, 40, 41 and 42, respectively, to the main circuit wires 43, 44, 45 and 46, leading around the aircraft to the various gunners' stations. A return circuit connector 47 is provided, connected to one terminal of each of the switch members 10', 12', 14', 16' and 25 and to one side of the battery 48 by the wire 49. The other side of the battery is connected to ground, as indicated at 50. Each conductor 39, 40, 41 and 42 has connected thereto a circuit wire 51, 52, 53 and 54 leading to a test switch 25. When this switch is closed, current will flow from the battery 48 through the conductors 49 to one side through the switch 25, to the conductors 51 to 54, and conductors 39 to 42, causing all lights on the panels to be illuminated.

Should any one of the switches to the individual lights 10, 12, 14 and 16 be depressed, for instance, the switch 10' in the wiring diagram in Fig. 5, corresponding to the switch 10' on the panel board 7a, shown in Fig. 2, current will flow from the battery 48 through the conductors 43 and 38, through the depressed switch 10', to the lamp 10, and through ground 30 back to the other side of the battery. Closing of the switch

10' also establishes a circuit through the conductor 40 to the conductor 44 leading to the other warning panels located at the other stations around the ship, such as 27 and 28 in Fig. 5. Current flows along the wire 44 and the other conductor wires 40 at the other stations to one terminal of the other lamps 10 at the last-mentioned stations. Since the second or other terminals of these lamps are all grounded at 30, current flows through all of the lamps 10 to the ground and back to the grounded terminal 50 of the battery 48, completing the circuit. Closing of another switch, such as 14' or 16' in the station 26 or 27, lights the respective lamps 14 or 16 in that station and, through the conductor 41 or 42, connects the battery 48 with the conductors 45 or 46 connected to one terminal of the lamps 14 and 16 in the other stations and, since the other terminals of these lamps are grounded to the battery, they are selectively lighted when the respective switches 14' or 16' are closed.

In the operation of the device, assuming an enemy aircraft 3 to be sighted on the right side of the plane A, and it appears that this target is to pass around the stern, one or more of the gunners in their stations, observing the enemy craft, will depress the push button switches 10', 11' or 12', depending to some extent on the location and probable direction of the enemy craft. This action by the gunners will cause the signal lamps 10, 11 and 12 on all of the panels 7a to be lighted, indicating to all of the gunners in all of the stations that the enemy is moving into the areas depicted on the panels where the signal lamps are illuminated. These gunners for these depicted areas, being so warned, are in a position to more readily locate the enemy craft and concentrate their fire upon it as it comes into the range of their guns.

In order to inform the gunners, not only as to the particular segment in which an enemy target may be, but also to indicate that the target is above, on or below the level of the horizon in a particular area, we provide a multiple push button signal unit, as illustrated in Fig. 4, each unit comprising a base, indicated at 55, carrying signal lamps 56, 57 and 58 and similarly located push buttons or switches 56', 57' and 58'. These multiple units may be located on the panel members 7a in the same positions as the lamp and switch units in Fig. 3. When the gunner depresses the upper button 56' of one of these multiple units in a certain area, the lamp 56 is illuminated in a corresponding location on all of the panels, indicating that an enemy aircraft is not only in that particular sector, but is above the horizon therein. The depression of the button 57' lights the lamp 57 and indicates that the craft is about on the horizon, while the depression of the button 58' lights the lamps 58 and indicates the target to be below the horizon.

This system is primarily designed for aircraft, but it is obvious that the same may readily be used for various protective systems, such as on ships, tanks, and even on stationary gun emplacements.

Having thus described our invention, in connection with an illustrative embodiment, what we claim as new and desire to secure by Letters Patent is:

1. In a protective signalling system for an aircraft having a plurality of associated control stations to protect predetermined associated areas thereof, signalling means therefor comprising a plurality of visual indicators, at least one of

which is located in each of the aforesaid control stations, each of said visual indicators having depicted thereon the approximate relative location of all of said associated areas, interconnected signalling means at each of said control stations, associated with each of the said depicted areas aforesaid on said visual indicators, and independently operable signal actuating means similarly located in each station, in each depicted area and connected with all of the signal means for the same predetermined areas, in all of the stations, to selectively actuate the last named interconnected signal means in any predetermined depicted area on all of said visual indicators.

15 2. In an aircraft gunner's signalling system of the class described having a plurality of gunners' stations for protecting associated predetermined areas of the craft, a signalling panel device in each gunner's station having depicted thereon the aforesaid associated predetermined areas, signal means in each of the depicted areas aforesaid on all of the said panel devices, and independently operable signal operating means in the depicted areas aforesaid for actuating similarly located signal means in any predetermined depicted area on all of said panel devices.

3. In an aircraft gunner's warning system of the class described having a plurality of gunners' stations disposed around a craft in associated 30 locations and protecting associated areas surrounding the craft, a warning panel member in each gunner's station having depicted thereon the replica of said craft and said associated protected areas, a signal device on each panel member located adjacent each depicted area aforesaid comprising a lamp and operating means therefor in each depicted area, and a connection from said operating means in each depicted area on any panel member to the lamps in the same depicted 40 area on all of said panel members for simultaneously operating all the lamps in a selected area on all of the panel members from any of the panel members.

4. In an aircraft gunner's warning system, a 45 plurality of panel members adapted to be disposed in the gunners' stations on an aircraft, each having a replica of an airplane on its face and a number of electrically interconnected warning-lamp-push-button combinations similarly disposed around the airplane replicas on all of the 50 panel members for selectively lighting said similarly-located lamps on all of said panel members.

5. In a signalling system for a plurality of separate associated protective control stations located in different associated areas around a common point to protect the same, signal means therefor comprising a plurality of visual indicators, at least one of which is located in each station and has depicted thereon the approximate 55 relative location of all of the aforesaid associated areas, visible signal means at each control station physically associated with each depicted location on said visual indicator, signal actuating means in each control station operatively and 60 physically closely associated with each of the visible signal means on the visual indicator in that station, and operatively connected to the signal means located in the other stations, depicting the same associated areas for causing simultaneous 65 actuation of all of the said visible signal means aforesaid, in any similarly located depicted location, on all of the visual indicators.

6. In an aircraft gunner's warning device, a 70 plurality of panel members each having a replica 75 of the aircraft depicted upon the face of the panel

member and a plurality of signal lamps and lamp-lighting push button units disposed on the panel around the depicted aircraft in the relative depicted areas covered by the guns of the aircraft, each unit comprising a row of lamps and a juxtaposed parallel corresponding row of push buttons for selectively lighting relatively oppositely disposed lamps in the row, said panel members being disposed at the gunners' stations for the said guns of the aircraft with the relatively

16

similarly located push button and lamp units on each panel electrically connected in parallel whereby any push button energizes and lights similarly located lamps on all of said panels indicating the depicted area covered by the guns protecting that area and the portions of that area located on the horizon level and above and below said level.

CHARLES L. PAULUS.
RAYMOND K. STOUT.
